UNITED STATES PATENT OFFICE

CHARLES STERN AND JAMES JOSEPH CARLOCK, OF JERSEY CITY, NEW JERSEY, ASSIGNORS, BY MESNE ASSIGNMENTS, TO ARDCO MANUFACTURING COMPANY, OF HOBOKEN, NEW JERSEY, A CORPORATION OF DELAWARE

RAILWAY-JOURNAL-OILING DEVICE

Application filed April 5, 1928. Serial No. 267,681.

The present invention relates to improvements in railway journal oiling devices and is a continuation in part of our prior similarly entitled application filed September 8, 5 1927, Serial No. 218,299.

The invention also relates to certain improvements over the device shown and described in the application of Charles Stern entitled Lubricating device, filed January 25, 10 1928, Serial No. 249,415.

It is an object of the present invention to provide a lubricating journal box or engine truck cellar, equipped with means for also lubricating the hubs of the truck, trailer or 15 driving wheels in order to prevent the rapid wear of the hub liners, which is a source of great nuisance and expense at the present time.

Another object of the invention resides in 20 providing a device to agitate the waste, so that the same will not pack against the rapidly rotating journal and become glazed thereby.

A further object of the invention is to provide improved means for retaining the dispensing strip for the lubricant in place. 25

With the foregoing and other objects in view, the invention will be more fully described hereinafter, and will be more particularly pointed out in the claims appended 30 hereto.

In the drawings, wherein like symbols refer to like or corresponding parts throughout the several views,

Figure 1 is a longitudinal vertical central section through an improved railway journal oiling device constructed according to the present invention. 35

Figure 2 is a fragmentary front end view of the same with the journal indicated in section. 40

Figure 3 is a top plan view of the cellar with parts broken away, and parts shown in section.

Figure 4 is a perspective view, with parts broken away showing the lubricating roller and its carrier. 45

Figure 5 is a rear end view of the device partly in section and showing the journal in section. 50

Figure 6 is a fragmentary plan view of the improved truck cellar, and

Figure 7 is a cross section taken therethrough.

Referring more particularly to the drawings, 8 designates the bottom of an engine truck, or trailer cellar, 9 and 10 the side walls thereof and 11 and 12 the front and rear walls respectively. 55

As shown in Figures 3 and 5, lubricant is 60 arranged to be contained in a cup or reservoir 13 and delivered through the pipe 14 to the cellar. The pipe 14 connects with a longitudinal channel 15 in the side wall 9. A similar channel 16 is provided in the opposite side wall 10. These channels are connected by the cross passage 17, so that oil flowing from the receptacle 13 will be received in both longitudinal channels 15 and 16. 65

The inner walls of these channels are provided with numerous perforations 18 for 70 leading the oil to recesses 19 containing felt or other oil absorbent strips 20. The side walls of the recesses 19 are of dove-tail form and the side walls of the strips 20 counter 75

parts thereof, whereby the strips will be retained in place. As a further security, strands of wire 21, best shown in Figure 1, are inserted over the strips 20. These wire strands are of zig-zag form and are resili- 80

ent. The wire is of such lateral dimensions normally, that it must be compressed and forced into the dove-tail groove 19; whereupon it expands against the inclined walls and is thus held securely in place. The wire 85

retains the strip 20 and prevents it from coming in contact with the rapidly rotating journal 22, which would result in the strip becoming glazed. 90

A glazed surface prevents uniform distribution of the oil thereover and actually prevents passage of the oil therethrough. The wall face 23 below each recess is provided with narrow slots 24 communicating with the outer portion of the recesses 19 and with the waste space below. The oil, which seeps through the capillary strips 20 will flow down through the slots 24 onto the waste in the cellar and keep this waste constantly and freshly lubricated. The action of the rotat- 95

ing journal tends to throw excess oil out toward the ends of the recesses 19 and, when the oil accumulates at the ends of the recesses, the oil is forced out from the cellar over the end walls. Much of this oil is wasted.

In order to divert this accumulated oil to the waste, there are provided large slots 25 and 26 near the ends of the recess. These 10 slots carry the excess oil down to the waste below.

A transverse partition 27 divides the cellar into two compartments, to both of which waste is supplied. In the present instance 15 the partition 27 carries long bosses 28 having bearing openings therethrough to slidably receive the rods 29 which are provided with the waste agitating pins 30. These pins may be screw threaded into the rods 29 or 20 otherwise secured therein. Such agitating pins are mounted in the main compartment and disturb and agitate the waste when the rods 29 are reciprocated. This agitation of the waste serves to prevent the waste from 25 becoming glazed with injury to its lubricating and capillary properties.

The rods 29 extend through the partition 27 and into the auxiliary compartment, where such rods are threaded or otherwise 30 secured to the roller carrier. The roller is indicated at 31, and it is shown in Figure 4 as journaled on a pin or pivot 32 which extends between the plates 33 and 34. These plates are spaced apart and are coupled by 35 the lugs 35 and 36 provided with threaded sockets to receive the threaded ends 37 of the rods 29. The ends of the rods 29 are preferably upset at the outer faces of the lugs.

40 These lugs provide shoulders 38 to take against the legs 39 on the confining plate 40 which fits above the top plate 33 of the roller carrier. The legs 39 are provided with the out-turned flanges 41 which fit against the 45 inside of the front wall 11 of the cellar and are secured thereto as by the rivets 42 or other fastenings. The front wall is curved, as indicated at 43 in conformity with the usual practice to receive the journal 22. This 50 front wall 11 is furthermore provided with the opening 44 to receive the roller and its carrier therethrough. The roller 31, as shown in Figure 1 extends against the wheel hub 45.

55 In Figure 1 is also shown an oil sump 46. This sump lies below the lowermost part of the opening 44 in the front wall 11 through which the roller and its carrier project. Such sump holds the oil which seeps down from the waste and would otherwise be lost through the roller opening.

The method of assembly is as follows:—

The roller carrier is assembled with the rods 29, before the plate 40 is put in place. 60 The coil springs 47 are slipped over the rods

29 and the rods are introduced through the opening 44 in the front wall 11 and through the openings in the bosses 28. Of course, the agitating pins 30 have not yet been put in place in the rods 29. The springs 47 take 70 against the partition 27 and are put under some compression in introducing the roller carrier into proper position.

The confining plate is then put on by slipping its legs 39 downwardly on opposite sides 75 of the roller carrier and against the shoulders 38. The flanges 41 are then riveted or otherwise secured in place. The roller and its carrier will thereupon be forced outwardly against the wheel hub 45 by pressure of the springs 47. The shoulders 38 will restrict the outer movement. Afterwards the pins 30 are put in place. Due to inequalities in the surface of the wheel hub; and due more so to the lateral motion of the locomotive, the 80 roller and its carrier will partake of a reciprocating motion, which will be communicated to the rods 29 and the waste agitating pins. The desired constant movement of the waste will result. Oil will be supplied to the waste 85 as heretofore described and the roller 31, rotating in contact with the waste, will receive oil and apply it to the hub 45 on the wheel, easing the hub's passage over the liner.

The device is applicable to both locomotive and car journals.

In Figures 5 and 6 the oil channels 15^a and 16^a are connected by the cross channel 17^a and are adapted to receive lubricant from a suitable source of supply as from a reservoir 13, shown in Figure 5. Ducts 18^a set up communication between the soil channels and the bases of the dove-tail recesses 19^a which contain the felt or other strips 20^a. In this instance the strips are not confined by 105 the wire strands, but the strips furnish oil to the waste in the cellar below.

It is obvious that various changes and modifications may be made in the details of construction and design of the above specifically 110 described embodiment of this invention without departing from the spirit thereof, such changes and modifications being restricted only by the scope of the following claims.

What is claimed is:—

1. In a railway journal box having recesses in communication with a source of lubricant supply, strips in said recesses, and zig-zag strands of resilient wire fitted forcibly into said recesses on top of the strips to 115 hold the same in place.

2. In a railway journal box, dove-tail recesses in communication with a source of liquid supply, the portions of the journal box below said recesses being provided with 120 numerous slots and with large end slots, absorbent strips in said recesses, and zig-zag strands of resilient wire normally wider than the recesses for fitting forcibly into the recesses and adapted to expand against the in- 125

- clined walls thereof to hold the strips in place.
3. A railway journal box for containing waste, means for automatically feeding and distributing lubricant to the waste, a roller device in contact with the waste and with the hub of the wheel for lubricating the latter, and waste agitating means coupled to said roller device.
4. A railway journal box for containing waste, means for automatically feeding and distributing lubricant to the waste, a reciprocating roller carrier, a roller carried thereby and adapted to come in contact with the waste and with the wheel hub, yieldable means to force the carrier outwardly, and waste agitating means movable with the carrier.
5. A railway journal box for containing waste, means for automatically feeding and distributing lubricant to the waste, a roller carrier mounted for agitating movement, a roller carried thereby in contact with the waste and with the wheel hub, a rod coupled to said carrier, and a series of pins on the rod movable through the waste.
6. A railway journal box for containing waste, means for automatically feeding and distributing lubricant to the waste, a roller carrier mounted for reciprocating movement through the front wall of the journal box, rods secured to the carrier, a partition in the journal box having bearings for the rods, springs surrounding the rods between the partitions and the carrier, and staggered pins on the rods extending into the waste.
7. A railway journal box for containing waste, means for automatically feeding and distributing lubricant to the waste, a roller carrier consisting of upper and lower plates and shouldered bosses connecting the plates, rods movable with the carrier and having waste agitating means, bearing means for the rods, and means to confine the roller carrier in place.
8. A railway journal box for containing waste, means for automatically feeding and distributing lubricant to the waste, a movable shouldered roller carrier, means to yieldably project the roller carrier, and confining means cooperating with the shoulder for holding the roller carrier against outer movement.
9. A railway journal box for containing waste, means for automatically feeding and distributing lubricant to the waste, a roller carrier movably mounted in the box, means for yieldably projecting the carrier, a confining plate adapted to extend above the carrier, legs on the plate extending upon opposite sides of the carrier, and flanges upon the legs for securing the legs and plate to the front wall of the journal box.
10. In a railway journal box containing waste, a lubricating member contacting with the waste in the box and with a hub of the wheel on which the journal box is used, and movable means carrying said member and embedded in the waste.
11. In a railway journal box containing lubricated waste, an agitating member in contact with the waste and with the hub of a wheel with which the journal box is associated, and means moving with said member mounted in the journal box and embedded in said waste for agitating the waste.
12. In a railway journal box for containing waste, vibrating means in the journal box for agitating the waste, and positive actuating means for the vibrating means operable during the movement of the locomotive to avoid the glazing of the waste.
- In testimony whereof we affix our signatures.
- CHARLES STERN.
JAMES J. CARLOCK.
